HONING MACHINE

John E. G. Kline, Grosse Pointe Farms, Mich., assignor to The Carborundum Company, Niagara Falls, N. Y., a corporation of Delaware

Application December 10, 1936, Serial No. 115,225

16 Claims. (Cl. 51—34)

The present invention relates to a machine for honing cylinders to a true contour and is specifically directed to a manner by which a rotating spindle carrying the honing tool is reciprocated in the bore of a cylinder of an internal combustion engine or the like including means for controlling the movement of the spindle.

In carrying out a cylinder grinding operation the honing tool is inserted in the bore to be finished and the same is rotated and reciprocated to abrade the cylinder wall. During the honing or finishing operation the tool must be longitudinally moved while rotated within such limits as will prevent the tool from passing out of the ends of the bore since the expanded abrasive stones will not permit the tool to reenter the cylinder. It is also necessary to move the tool back and forth lengthwise of the cylinder to points adjacent the ends thereof so as to prevent excessive abrading along the central portion of the bore as compared to the grinding at the ends. In other words "barrel shaping" of the cylinder surface must be avoided. The reciprocation of the tool must therefore be positive and the length of the recurring stroke must be the same for each reversal irrespective of the reciprocating speed to provide a perfect cylindrical finish to a given cylinder.

It is therefore an object of the invention to provide a machine adaptable to such a honing operation in which one or more honing tools are operatively supported by a reciprocatory spindle having a driving mechanism operating to effect rotation of the tool or tools simultaneously with the proper reciprocatory movement.

In certain types of honing machines of the prior art the spindle has been reciprocated by means of a hydraulic mechanism to provide smooth reversal of the spindle which cannot be obtained conveniently by the use of wholly mechanical mechanisms. The longitudinal movement of the spindle by means of a hydraulically actuated piston directly connected to reciprocate the spindle through a stroke corresponding to the movement of the piston has the undesirable characteristic of requiring an intricate control mechanism to reverse the stroke at a proper point for the various lengths of work cylinders. Even after the control mechanism has been adjusted to give the proper length of stroke changes in speed of reciprocation will cause the reversing point to change by reason of the altered inertia of the spindle structure.

Such a machine is impractical for use in driving a honing tool in certain types of cylinders

such as the closed end type employed in many airplane engines. That is to say, the bore of such a cylinder must be abraded lengthwise thereof to a point immediately adjacent the closed end and the point of reversal must therefore be definite and positive. The tendency of the hydraulic operated machines known to the art to overrun or underrun render them unsatisfactory for finishing such types of cylinders.

A further object of the invention is therefore to provide a mechanism for effecting reciprocatory movement of the honing tool with means by which the length of the stroke may be adjusted for operation in a given cylinder whereby the character of the reciprocating mechanism will cause the tool to be positively moved within definite limits.

Another object of the invention is to provide a mechanism wherein the honing tool is moved longitudinally of the cylinder in such a manner that each back and forth movement is exactly the same and to supplement such a mechanism with simple means for withdrawing the tool from the cylinder at the end of the honing operation.

Other and further features and objects of the invention will be more apparent to those skilled in the art upon a consideration of the accompanying drawings and the following description wherein an exemplary embodiment of the invention is disclosed.

In the drawings:

Fig. 1 is a perspective view of the machine showing the front and left sides.

Fig. 2 is a front elevation of the machine with part of the casing broken away.

Fig. 3 is an elevation in part section of the machine from the right side.

Fig. 4 is a section on line IV—IV of Fig. 3.

Fig. 5 is a view of the reciprocating mechanism mounting assembly with the reciprocating cylinder and associated parts in section.

Fig. 6 is a detail of the liftout cylinder assembly.

Fig. 7 is a part section through the top of the machine showing details of the speed changing mechanism.

Fig. 8 is a diagrammatic view of one form of control mechanism showing valves 5, 6 and 11 in section.

Fig. 9 is a section on line IX—IX of Fig. 5.

Fig. 10 is a view of the reciprocating cylinder assembly looking from the front of the machine.

Fig. 11 is a hydraulic circuit diagram of the machine.

Fig. 12 is a diagrammatic view showing the

positions of the various valves when the reciprocating cylinder is traveling upwardly and the spindle is traveling downwardly.

Fig. 13 is a diagrammatic view, similar to Fig. 5 12, except that the valves are shown as they are when the reciprocating cylinder is traveling downwardly and the spindle is traveling upwardly.

Fig. 14 is a diagrammatic view which illustrates the positions of the valves 6, 7 and 8 when the lever F has been thrown to stop the machine.

Referring specifically to Figs. 1, 2 and 3, the machine comprises a base 100 on which is mounted an upright body portion referred to generally 15 as 101.

The lower part of the body portion houses an electric motor 102 which constitutes the prime mover of the machine (see Figure 3.) This motor drives a pump 103 (see Fig. 4) which supplies 20 fluid pressure to the various hydraulic cylinders and valves, and also furnishes rotative power to the honing tool 104 through the intermediary of shaft 175, gear train 176, pulleys 177 and 177'; clutch G, gear trains 178 and 179 and splined 25 shaft 110'. Hand wheel 115 is for the purpose of varying the rotation speed of the hone. The speed changing mechanism will be described later on in this specification.

The honing tool 104 is of the type well known 30 in the art and consists essentially of a head 105, which has a number of radial slots in which abrasive stones are mounted. These stones are adapted to be adjustable radially of the head so that the head can be inserted into the bore of 35 the workpiece and the stones expanded to engage the cylinder wall.

The motor 102 also drives, through the belt 99, a coolant pump which supplies coolant from the sump 98 to the bore of the workpiece 97.

40 The workpiece 97 is supported on a table 96 which is vertically adjustable by means of jack-screw 95.

As stated above, the honing operation requires 45 that the tool be reciprocated in the bore as well as rotated, and the mechanism for reciprocating the tool comprises essentially a normally stationary cylinder C, hereinafter referred to as the "liftout" cylinder, a reciprocating cylinder D, and a gear sector member B.

50 Gear sector member B is provided with two sets of gear teeth 106 and 107 which are adapted to mesh respectively with the rack 108 on the liftout cylinder C and rack 109 on the spindle A.

Gear sector member B is also provided with 55 a pivot pin 110 which is mounted in a cross-head 111 for sliding movement under the influence of the connecting rod K. The crosshead 111 is mounted in the body wall as shown in Fig. 3.

The connecting rod K is connected at its 60 opposite end with the crank E which is in turn fixed to the shaft 114. Shaft 114 is journaled in the rear of the plate 300 (see Figs. 2 and 9) and has the pinion 115 keyed thereon. The teeth of pinion 115 mesh with rack 116 which is on 65 the outside of the reciprocating cylinder D.

Crank E is adjustable as to throw and consists of (see Fig. 10) a channel shaped member 113 fixedly mounted on the outer end of shaft 114, and a slidale member 113', which carries 70 the crankpin 71 on which the lower end of the connecting rod K is journaled. An adjusting screw 70 is mounted, by means of a suitable thrust bearing 72, in the lower end of the channel shaped member 113. It will be apparent from 75 Fig. 10 that the crank throw may be adjusted

by applying a wrench to the head on the bottom end of screw 70.

The details of the reciprocating cylinder D are shown in Fig. 5.

Cylinder D and its associated mechanism, are 5 mounted on a plate 300 (Figs. 2, 5, 9 and 10) which is removable from the housing by loosening bolts 301.

Cylinder D is mounted for sliding movement on the piston 302 and piston rod 303, the latter 10 of which is fixed at each end to the supports 304 and 305 of plate 300.

The piston rod 303 has longitudinal passageways 306 in each end thereof. These passageways extend into the piston rod to points closely 15 adjacent each other, as shown by Fig. 5, and each communicates with the interior of the cylinder by means of ports 307 and 308 one of which is provided with a ball check 309. Cylinder head 310 is provided with a cylindrical extension 310' 20 which extends a considerable distance into the bore. This cylindrical extension 310' cooperates with ports 307 and 308 to effectively cushion the shock when the cylinder D reverses its direction of movement. 25

As is obvious from the drawings, when the cylinder D approaches the end of its stroke in the downward direction, passageways 307 (of which there are four) are cut off by the cylindrical extension 310' and the oil which was being exhausted through passage 306 is cut off before the piston 302 comes in contact with the end of the extension 310'. Because the ball check 309 is closed by the spring, a quantity of oil is trapped between the piston and the extension and thus 30 forms a cushion. 35

On the other hand, when the flow of oil is reversed by means of pilot valve 7 and valve 6, the passageway 307 is still closed by the extension 310' and the oil pressure can reach the 40 expansion chamber through the passage 308 only. Due to the fact that this passage is restricted by the spring biased ball 309, the flow of oil into the expansion chamber is retarded so that a gradual reverse of the cylinder is obtained. As 45 soon as the cylinder moves upwardly far enough so that the passageway 307 is uncovered, then the movement is accelerated to its full speed until the end of the stroke is reached in the other direction. It is of course to be understood 50 that the construction of cylinder D is identical at both ends.

Liftout cylinder C will now be described in detail. This cylinder is used for inserting the honing tool into the bore of the workpiece and for 55 withdrawing it therefrom at the end of the honing operation. During the time which the workpiece is being honed cylinder C occupies a stationary position at the top of its stroke.

Referring to Fig. 6, liftout cylinder C comprises 60 an outside casing 200 on which is mounted a rack 108 which has teeth adapted to mesh with teeth 106 on the gear sector member B. Piston rod 202 is mounted at its upper end on a projecting shelf 203 which projects from the 65 rear side of the machine casing (Figs. 3 and 6), and at its lower end on a similar projecting shelf 204.

Journaled on the rod 202 at its lower end is an elongated adjusting nut 205. This adjusting 70 nut has threads 206 on its outer side which engage complementary threads 207 on member 204. Thus it can be seen that by screwing the member 205 upwardly or downwardly the downmost position of the cylinder C can be accurately fixed. 75

Piston 207 is fixed on the rod 202 which has a hollow bore 208. This bore forms a passageway which communicates with the expansion chamber 209 through ports 210. The construction of the upper end of the cylinder C is identical with this.

Thus it can be readily seen that fluid pressure entering the chamber 209 by way of passageway 208 and line 16 under the control of valve 5, will cause the cylinder to move upwardly to the limit of its stroke thereby moving spindle carrier A downwardly into the bore of the workpiece. At the same time oil is being exhausted through port 210, passageway 208 and lines 15 and 17 back to the tank I.

Conversely, when it is desired to withdraw the hone from the bore of the workpiece, valve 5 is positioned so that fluid pressure is introduced into the chamber 209 through ports 210, passageway 208 and line 15 and simultaneously oil is exhausted from chamber 209 through port 210, passageway 208 and line 16.

It is necessary in a machine of this type to provide some means for varying the speed of rotation of the tool as well as the speed of reciprocation thereof.

In the instant case, the power of reciprocation is controlled by adjusting the spring in valve 3 as is obvious from Figs. 12 and 13. A change in the spring pressure will cause an increase or decrease in the fluid pressure and a corresponding increase or decrease in the power of reciprocation of cylinder D.

The speed of rotation of the tool is varied by means of the mechanism shown in Fig. 7 which comprises essentially two variable pulleys 177 and 177' and a shifter lever 116.

Pulley 177 consists of a stationary part 117 journaled on the reduced end portion of drive shaft 118, and a relatively movable part 119 which is mounted for rotation on the stub shaft 121 and the projecting portion 120 of part 117.

Pulley 177' is larger in diameter than pulley 177, but is similar in construction thereto, as can be readily seen from Fig. 7. Pulley 177' is journaled on the driven sleeve 123 and drives the shaft 122 through the clutch 124. Clutch 124 is of the twin disc type and is engaged and disengaged by the fluid pressure cylinder G.

Speed change lever 116 is mounted on the casting for lateral swinging movement by means of pivot pin 125 as is apparent from Fig. 7. This is pivotally connected to the movable elements of pulleys 177 and 177' at 126 and 127 respectively. The extreme lower end of lever 116 is engaged by the traveling nut 128, which is in turn mounted on the screw 129. Screw 129 is rotatable by means of handwheel 115.

Thus it can be seen that rotation of the wheel 115 causes the lever 116 to swing about pin 125 in a direction corresponding to the direction of rotation of the wheel. This results in a movement to the left of the movable section 119 of pulley 177 and a complementary movement to the right of section 119' of pulley 177', or vice versa as the case may be.

The belt 150 is of the well known V-type and rides in the pulleys 177 and 177'. It will be obvious that as the effective diameter of pulley 177 is increased (by moving section 119 toward the left), the belt will move radially outwardly of the pulley and at the same time section 119' of pulley 177' will be moved toward the right (under the influence of lever 116) thus decreasing the effective diameter of pulley 177' and

causing the belt 150 to move radially inward.

The pointer 146 indicates on the scale 147 the speed ratio at which the machine is set.

The lever F controls the starting and stopping of the honing operation and is positioned on the left side of the machine. Control valves 5, 8 and 11 are directly associated with the lever F, and the operation thereof may be seen from a reference to Fig. 8.

Lever F is mounted on a rod F' which also carries cams H, H' and H''. Cam H'' has a longitudinal groove into which the stem of valve 11 enters when the machine is at rest.

Cams H and H' control the stems of valves 8 and 5 respectively as is obvious from the drawings.

The lever J may operate the stem J' of valve 8 through a rack and pinion, as shown in Fig. 8, or a finger and V-lever may be used, as is indicated diagrammatically in Fig. 11.

The operation of the device is as follows:

In Fig. 11 the device is shown diagrammatically, the positions of the various parts being shown as they are when the spindle travel is downward.

Before beginning the honing operation the operator first closes the switch (not shown) in the electric power circuit which starts the electric motor 102.

The hydraulic pump 103, which is directly driven by motor 102, then draws oil from the tank I through line 12 and forces it through line 13 into valve 3, which latter regulates the amount of oil which is allowed to enter the operating system through the main supply line 14. The surplus oil in excess of that used is returned to the supply tank through line 29, and control valves 5 and 6 are supplied with pressure through lines 14A and 14B respectively. Check valve 4 guards the system against excess pressure. Valve 11 is also supplied with pressure through line 28.

Reference is now made to Figs. 11 and 12. Fig. 12 shows the position of the valves when the cylinder D is traveling upward and the spindle is traveling downward.

To start the honing operation, the operator throws the control lever F into the first intermediate position P (see Fig. 11). This closes valve 11 thereby shutting off the flow of oil from pilot line 28 to 27B and causes a build up of pressure in the lines by reason of the fact that as soon as oil ceases to flow through line 28, the pressures in chambers X, Y and Z of valve 3 become equal thus allowing the spring to seat piston R.

The operator then by moving the lever F into the second intermediate position P' depresses the piston in valve 5 causing oil to flow from 14A into line 16 thereby bringing the liftout cylinder C upward and moving the spindle carrier A downward to the top of the working stroke, and positioning the honing tool in the workpiece.

The lever F is then moved to position R or "run" position. This causes link J to throw pilot valve 8 (which receives pressure through line 20 and ports P and 131 of valve 7) thus causing oil to flow from line 21 to lines 26, 26A and 26B. The pressure on line 26B throws clutch cylinder G into "run" position and pressure on line 26A 70 throws valve 6 into such position that pressure flows from 14B to line 23, thus bringing the cylinder D upward and rotating crank E downward to produce the initial working stroke.

Simultaneously the oil on the opposite side of

the piston in cylinder D is exhausted through line 24A against the back pressure of foot valve 9 to lines 24 and through the lower exhaust port of valve 6 to lines 17C and 17A, through foot valve 10 which for the moment is in series with foot valve 9, and then through line 17D to the storage tank.

Turning now to Fig. 13, when cylinder D reaches its upper limit of travel, the finger 130 (see Fig. 11) throws the pilot valve 7 so that pressure from line 20 is directed through the full line passage in valve 7 and through line 22 to valve 6. Valve 6 responds by reversing the flow of oil from line 23 to line 24 which in turn causes oil to flow from line 14B through line 24 and foot valve 9 (which is now operating under free flow) into line 24A leading to the bottom of cylinder D. This causes cylinder D to travel downwardly and the oil in the top of cylinder D is discharged to the tank through line 23, the upper exhaust port in valve 6, line 17C, line 17A, foot valve 10 and line 17D. Note that in this case, foot valve 10 alone is acting to cushion the shock of reversal of cylinder D. As cylinder D reaches its lower limit of travel, the finger 130' throws the pilot valve 7 and the above described cycle of operations is repeated until the honing operation is completed or it is desired to check the size of the bore of the work-piece.

Pilot valve 8 is fed from port 131 of pilot valve 7 through line 21; thus it will be seen that when pilot valve 7 is thrown as shown in Fig. 13, pilot valve 8 receives no oil flow. When valve 7 is thrown as shown in Fig. 12, pressure oil flows through line 20, ports P and 131 of valve 7, line 21, ports P' and 131' of valve 8 and thus to line 26. It is therefore obvious that on each downward stroke of cylinder D, the clutch cylinder 40 G receives an impulse of oil through line 26B which tends to keep the clutch in engaged position.

When it is desired to stop the machine (see Figs. 11 and 14), lever F is thrown downward to position P'. This causes valve 8 to reverse its flow and line 26 is connected through the dotted passage in valve 8 to line 27A thereby exhausting oil back to the tank.

When this occurs the next downward movement of the V lever on valve 7 (under the influence of finger 130') throws the ports of valve 7 so that pressure fluid flows from line 20 into line 21 and fluid is exhausted from lines 22 and 17C through lines 19 and 17B. This precludes further movement of the piston in valve 6 and causes cylinder D to stop in its downmost position. The pulsating pressure (which occurred during reciprocation of the cylinder D) now become constant pressure transmitted through lines 20, 21 and 25 from valve 8 and the clutch is thrown out thereby stopping the rotation of the spindle.

The operator then moves lever F to position P. This permits the piston of valve 5 to move outwardly and lines 14A and 15 are connected thereby allowing pressure fluid to flow through line 15 to cylinder C. This causes liftout cylinder C to move downwardly resulting in a rotary motion only of gear sector B (pin 110 is now stationary due to the cessation of movement of cylinder D) and a consequent addition upward movement of spindle carrier A which withdraws the honing tool from the workpiece.

By moving lever F downwardly to position S (or "stop" position), the valve 11 is opened there-

by connecting line 28 with lines 27 and 29. The piston in valve 3 will now unseat and the pressure in the system will drop to that of the spring.

The machine is now at rest and the workpiece 9 may be removed from the platform 96 and another workpiece placed thereon without disturbing the adjustment of the platform 96. This feature is of great importance in production honing because once the position of the platform and the length of stroke of the cylinder D are fixed, it is unnecessary to change these until it is desired to hone a workpiece of different length.

Valve 18 is a simple needle valve and is merely provided as an adjusting means to limit the time of reversal of valve 6 at the extremities 15 of the stroke. In other words, the length of dwell at the extremities of the working stroke can be regulated by regulating the orifice in the needle valve 18.

Foot valves 9 and 10 function as back pressure valves to prevent "jumping" of the hydraulic cylinders during their motion. On the downward stroke of the machine spindle, foot valves 9 and 10 are in series, but on the upward stroke foot valve 10 only functions. The reason for this is 23 that an effective counterbalancing means may be obtained when very heavy hones are installed on the machine spindle. Ordinarily the mechanical parts of the machine are fairly in balance (due to the downward movement of cylinder D 30 occurring simultaneously with the upward movement of the spindle carrier A, thus effecting a counterbalance), without the use of valve 9 in the circuit. However, depending upon the weight of the equipment suspended from the spindle, 35 valve 9 may be adjusted to furnish a back pressure or resistance which will counterbalance the same. It will be noted from Fig. 11 that valve 10 functions as a back pressure valve on both sides of both cylinders C and D because it is injected directly in the return line from both of them.

Valve 6 is provided, at each of its ends, with manually operable means for regulating the rate of fluid flow into and out of said valve from and 45 into lines 22 and 26A. See Figs. 12 and 13.

This means comprises tapered screws 250 and 251. By adjusting the size of the openings in each end of the valve 6, the amount of fluid flowing may be regulated and thus the length of 50 time necessary for reversing the valve may be varied.

In honing closed end bores, the upper end of the honing tool passes beyond the open end of the bore a fraction of an inch, then reverses its 55 stroke. It is obvious that the bore receives more abrading at this end than it does at the closed end providing the speed of reversal is the same at both ends of the stroke.

In order to prevent the bore from becoming 60 "bell mouthed", the valve 6 may be adjusted so that a longer time is required to reverse the stroke when the tool is in the bottom of the bore. Thus, the hone remains at the bottom of its stroke for a longer period of time with consequent equalization of the abrading action.

It is obvious from the above description that this invention is not limited to a honing machine, but is equally adaptable to a machine for drilling, grinding, lapping or burnishing, and it 70 is not desired to limit the invention except as defined by the claims annexed hereto.

I claim:

1. In a honing machine comprising, in combination, a sectional dumbbell shaped gear seg- 75

ment having gear teeth arranged along the arcuate ends thereof, the teeth of one end engaging a rack gear carried by a longitudinally movable spindle, the teeth carried by the opposite end of said segment engaging a normally stationary rack gear to form a rolling fulcrum for said segment when the same is pivoted by movable means applied at a joint intermediate of its ends to longitudinally move said spindle a predetermined distance, means for holding the intermediate portion of said segment in a fixed rotatable position while said normally stationary rack gear is moved to abnormally pivot said segment whereby the spindle is moved beyond said predetermined position.

2. In a honing machine comprising, in combination, a fluid pressure supply, a hydraulically reciprocable cylinder connected to said supply, means operably responsive to the movement of said cylinder for reversing the movement of said fluid to said cylinder, a crank pin associated with the cylinder adapted to be oscillated by the reciprocation thereof, a longitudinally movable spindle, means for transmitting the oscillating movement of said crankpin to longitudinally reciprocate said spindle, and control means adapted upon operation to stop the reciprocation of said cylinder and the reciprocation of said spindle at one end of the stroke.

3. In a machine for honing a cylinder comprising, in combination, a fluid pressure supply, a hydraulically reciprocable cylinder, means associated with said fluid supply operably responsive to the movement of said cylinder to alternately direct fluid pressure to the opposite ends thereof to continually reciprocate said cylinder, a pinion gear associated with said cylinder adapted to oscillate a crank arm carried thereby through substantially an 180° arc, a longitudinally movable spindle, mechanical means for transmitting the movement of said crank arm to said spindle whereby the same is moved within limits described by the radius of said crank arm and manually operable control means cooperating with said first mentioned means adapted upon operation thereof to divert the supply of fluid from said cylinder when said crank arm thereafter reaches one end of said arc.

4. A honing machine comprising in combination, a longitudinally movable spindle, means for rotating the spindle, a rack gear carried by the spindle, a gear segment having arcuate shaped ends and gear teeth arranged along the ends, the teeth at one end of said gear segment engaging said rack gear and the teeth at the opposite end of said segment engaging a normally stationary gear rack, hydraulic operated reciprocating means for swinging said gear segment about said stationary gear rack whereby the spindle is longitudinally reciprocated.

5. In a honing machine comprising, in combination, a longitudinally movable spindle, means for rotating the spindle, a rack gear carried by the spindle, a sectional dumbbell shaped gear segment having teeth arranged along the arcuate ends thereof and movably mounted with the teeth at one end meshing with the teeth of said rack gear and the teeth of the opposite end engaging a normally stationary rack gear, a lever associated with an intermediate portion of said gear segment adapted upon movement thereof to pivot the segment thereby longitudinally moving the spindle by having the stationary rack gear act as the fulcrum for said segment.

6. In a honing machine comprising, in com-

bination, a fluid pressure supply, a hydraulically reciprocable cylinder, a crank associated with said cylinder adapted to be oscillated by the reciprocation thereof, a floating member engaging a longitudinally movable spindle at one end thereof and a normally stationary hydraulically movable cylinder at its opposite end, means connecting an intermediate portion of said floating member with said oscillating crank to reciprocate said spindle within predetermined limits, manually operable control means associated with said fluid supply and said cylinders movable in one direction through a plurality of predetermined positions, said control means being movable to one position to stop reciprocation of said first mentioned cylinder at one end of the stroke thereof, said control means being adapted upon additional movement to another position to direct fluid pressure to said normally stationary cylinder whereby said floating member is pivoted about said intermediate portion and thus move said spindle beyond said predetermined limits.

7. A honing machine comprising, in combination, a casing, a honing spindle, a rotatable tool associated with the spindle, a gear rack mounted on the casing in a normally stationary position, lever means connected with the spindle and having teeth thereon in mesh with said gear rack teeth, means for rotating said tool, means for oscillating said spindle about said rack as a center, and means for changing the position of said rack so that the spindle will be oscillated to an abnormal position.

8. In a honing machine, a honing spindle adapted to be reciprocated in the bore of a workpiece, means for reciprocating said spindle within accurately predetermined limits comprising a fluid pressure reciprocating cylinder, a gear rack on said cylinder, a pinion in mesh with said rack, a crank driven by said pinion shaft and an oscillating gear sector member driven by said crank.

9. In a honing machine, in combination, a honing spindle adapted to be reciprocated in the bore of a workpiece, means for reciprocating said spindle within accurately predetermined limits comprising a fluid pressure reciprocating cylinder and a sector member which is adapted to be oscillated about a displacable center by said cylinder, means for reciprocating said spindle beyond said predetermined limits, comprising a second fluid pressure cylinder, said cylinder being operable only when said first cylinder is stationary at the bottom of its stroke.

10. In a honing machine, a honing spindle, having teeth thereon, a normally stationary lift-out cylinder, a gear sector member adapted to pivot on the liftout cylinder and having gear teeth which mesh with the teeth on the spindle, and means for oscillating the gear sector member.

11. In a honing machine, a honing spindle having rack teeth thereon, a normally stationary liftout cylinder having rack teeth thereon, a gear sector member having oppositely disposed sets of teeth adapted to mesh with the spindle teeth and the liftout cylinder teeth respectively, means for oscillating the gear sector member about the liftout cylinder whereby the spindle is reciprocated.

12. In a honing machine, a spindle provided with a honing tool which is adapted to be rotated and reciprocated simultaneously, means for rotating the tool, means for reciprocating the tool, said last named means comprising a reciprocating cylinder, a normally stationary cylinder and a lever pivoted on the last said cylinder a

- adapted to be reciprocated by the reciprocating cylinder.
13. In a honing machine, in combination, a honing spindle adapted to be reciprocated within the bore of a workpiece, a rotatable honing tool mounted in said spindle, means for reciprocating said spindle, means for rotating said tool, separate means for withdrawing said spindle and tool from the bore of the workpiece, a control lever adapted to be moved to a plurality of positions, one of which causes the stopping of the reciprocating and rotating means and another of which causes operation of the withdrawing means.
14. A honing machine having a spindle member adapted to oscillate in a bore of a workpiece, a normally stationary liftout member, means for oscillating the spindle member about a center located on the liftout member and means associated with the liftout member for displacing said center for the purpose of withdrawing the spindle from the workpiece.
15. In fluid pressure actuated mechanism, in combination, a fluid pressure reciprocating cylinder, a source of fluid pressure, a fluid supply tank, pressure lines connecting said cylinder with said source, exhaust lines connecting said cylinder with said tank, a pair of back pressure valves connected in the exhaust lines in such relationship that one of the said valves is in series with the cylinder on the downstroke thereof and both of said valves are in series with said cylinder on the upstroke thereof.
16. In a honing machine, in combination, a honing tool, mechanical means for rotating said tool, fluid pressure means for positioning said tool in a workpiece, separate fluid pressure means for reciprocating said tool within the workpiece, a manually operated control lever adapted to be moved to a plurality of positions, one of said positions causing the first-named fluid pressure means to position the tool in the workpiece and another of said positions causing the second-named fluid pressure means to reciprocate the tool and the mechanical means to rotate the tool.
